HAND BRAKE MECHANISM

Raymond C. O'Connor, Chicago, Ill., assignor to
 Union Railway Equipment Company, Chicago,
 Ill., a corporation of South Dakota

Original application December 26, 1935, Serial
 No. 56,183. Divided and this application April
 22, 1937, Serial No. 138,358.

1 Claim. (Cl. 74—505)

This application is a division of Serial No. 56,183, filed December 26, 1935.

The present invention is directed to a hand brake for railway cars, which makes provision for quickly and easily taking up the slack in the brake rigging, and the invention relates particularly to the construction and arrangement of the pawl and ratchet mechanism and the hand wheel for actuating the gear and winding drum.

10 Further objects and details will appear from a description of the invention in conjunction with the accompanying drawings, wherein—

Figure 1 is a front elevation of the brake mechanism showing the hand wheel partly broken away;

Fig. 2 is a sectional elevation taken on line 2—2 of Fig. 1;

Fig. 3 is a detail of the pawl and ratchet mechanism taken on line 3—3 of Fig. 2, looking in the direction of the arrow; and

15 Figs. 4, 5 and 6 are details showing the pawl and ratchet mechanism in different positions of operation.

The operating portions of the brake mechanism which includes the features of the present invention are enclosed within a frame comprising a front cover plate 10, a rear wall 11, end walls 12, and an arched over top wall 13. The end walls and top wall are formed integrally with the 20 rear wall, and the front plate is secured thereto by rivets 14 or other suitable fastening means.

The front cover plate, as shown, is provided with an outwardly extending protuberance 15 in its lower portion, of arch shaped configuration, 25 and in the center of said protuberance the metal is outwardly bulged to afford a center boss 16 which receives the forward end of a gear wheel axle 17 provided with a flanged head 18 which fits into a recess 19 formed in the inwardly protruding boss 20 on the rear wall 11 of the frame.

30 The front end of the axle extends beyond the plane of the inner face of the protuberant lower portion of the front plate and abuts against the inner face of the boss 16, being held in place by a cotter pin 21 or other suitable fastening. The axle 17 is surrounded by a forward bushing 22, a rear bushing 23, and an intermediate bushing 24.

35 The forward and intermediate bushings are provided at their outer ends with flanges 25 which in conjunction abut against the ends of the hub 26 of a winding drum 27 which is journaled upon the bushings. The forward bushing 22 abuts against a bridge plate 22a which spans 40 the space across the protruding boss 16 and has

its ends integrally formed with the end walls of the frame. This arrangement brings the forward and rear ends of the shaft 17 into direct alignment with supports which are integrally formed in the frame, so that a very rigid and rugged construction is provided and the shaft is accurately aligned within integrally formed portions of the frame.

45 The winding drum is provided with a bifurcated web portion 28 furnishing a groove or channel 29 flanked on either side by the smooth cylindrical faces 30 of the periphery of the drum, which configuration affords a winding surface for the alternate links 31 of a brake chain, the intermediate links 32 standing in transverse relation and in position to enter the center groove or channel 29 in the winding drum, so that as the chain is wound up, the alternate links will lie flatwise upon the drum surface with the intermediate links standing edgewise within the 20 groove.

50 The bushing 23 furnishes the bearing for a gear wheel 33 having a web 34, a hub 35, and a toothed rim 36. The web is provided at a suitable point with a forwardly projecting boss 37 provided with a bore 38 to receive a headed bolt 39 which extends through a hardened collar 40 which furnishes an anchorage for the terminal link of the brake chain, the anchorage being in alignment with the plane of the groove in the 30 winding drum.

55 The above features of construction form the principal subject matter of invention described and claimed in the application of which the present is a division, and it is not the intention 35 to limit the use of the pawl and ratchet mechanism presently to be described to gears and drums of the special character referred to or to any particular type of gear and drum arrangement.

The teeth of the gear wheel 33 mesh with 40 pinion teeth 41 on a hand wheel shaft 42, the forward portion 43 of which projects through an aperture 44 in the front cover plate 10. The forward portion 43 of the shaft is squared and tapered and terminates in a threaded stem 45 45 entered through a square tapered bore 46 in the hub 47 of a hand wheel 48. The hub as shown is inwardly elongated and provided with a square uniform bore in its center portion 49 to clear the surface of the square tapered portion of the 50 shaft. The forward end of the hub, however, is provided with a square tapered bore 46 offset with respect to the uniform center bore and which aligns obliquely with a square tapered bore 51 at the inner end of the hub, so that these two 55

terminal portions of the hub will come into wedging contact with the surface of the square uniformly tapered shaft 43, being held in clamped relation thereon by a nut 52 threaded on to the 5 stem 45. The shaft 42 in advance of the gear teeth 41 is enlarged to afford a ratchet wheel 53 having ratchet teeth 54 of saw-tooth formation. Between the ratchet wheel portion of the shaft and the square tapered portion, the shaft is 10 cylindrically formed to afford a bearing surface 55 working within a bushing 56 which cooperates with a rear bushing 57 housed in a boss 58 in the rear wall to afford separated bearing surfaces for the hand wheel shaft.

15 The ratchet wheel 53 coacts with a pawl 59 having a tooth 60 positioned to engage with the abrupt faces of the ratchet teeth, and a pawl is carried by a hub 61 provided with a center axial bore 62. The hub at its inner end is provided 20 with an outwardly protruding segmental stop 63 extending through approximately 120°, the ends of which furnish stops for engagement with the ends of a segment 64 formed on or rigidly secured to a coaxial handle shaft 65 upon which the pawl hub is pivotally mounted for limited rotation. The handle shaft at its forward end carries a 25 handle 66 which extends beyond the cover plate and frame, as shown in Fig. 1, and terminates in a weighted end portion 68. The hub 61 is provided with a counterweight 69, which assists in the release of the pawl tooth 60. The 30 relationship of the handle shaft 65 with its segment 64 to the segmental stop 63 is one which permits the handle shaft to be turned freely through approximately 120° before the end of the segment 35 64 abuts against the inner end of the pawl stop 63.

The bushing 55 is carried by a boss 70 formed in a plate 71 which is riveted to the end walls of 40 the frame and stands in abutting relation to the inner face of the front cover plate when the parts are assembled.

With the pawl in engagement with the ratchet teeth as in Fig. 4, the weighted handle 66 will lie 45 in a position below the horizontal, and the contact of the forward end of the segment 64 with the upper end of the segmental stop 63 will serve to hold the pawl in engaged position. As the handle is lifted and turned beyond its vertical position, 50 as in Fig. 5, the rear end of the segment 64 will engage with the lower end of the segmental stop 63, and further movement will cause the disengaging of the pawl tooth from the ratchet wheel.

The rearward movement of the handle 66 is 55 limited by a tooth 72 at the base of the handle which is adapted to abut against the stop 73 on the wall of the frame. The arrangement is one which permits the handle to be lifted freely upward and past the medial position without 60 encountering any resistance, so that it is possible to effect a hammering action against the pawl segment 63, which may be highly desirable in cases where from freezing or other causes there

is a tendency for the pawl tooth to lock with the ratchet wheel.

As shown in Fig. 6, after the pawl tooth has been carried clear of the ratchet teeth by the thrust of the handle 66, it will be swung further 5 outwardly by the counterweight 69 until the pawl strikes the wall of the frame, which limits its outward movement.

The pawl is held in mesh with the ratchet in the "on" position by the weight of the release 10 handle, and this arrangement enables a brakeman to force the pawl into engagement with the ratchet by pressing down on the handle in case the pawl should stick while in the "off" position. In releasing the brake, the handle is 15 thrown about 40° past the vertical line, and in normal operations the operator will then turn the brake wheel sufficiently to take the strain off the pawl, which allows the handle to drop farther to the right and disengage the pawl 20 from the ratchet. However, if difficulty is encountered in effecting the release, force may be applied to effect disengagement of the parts in the manner described.

The ratchet shaft with the pinion teeth there- 25 on, as well as the pawl and pawl release handle, are journaled in the rear wall of the frame, and the front ends are journaled in a plate secured to the frame in the manner described, so that with the parts thus assembled the working mech- 30 anism throughout will be accurately aligned and held against displacement irrespective of the cover plate which simply performs the function of a closure for the frame and the working parts, which constitute a self-contained unit.

Although the invention has been described with particularity as to detail, it is not the intention, unless otherwise indicated, to limit the invention strictly to the mechanism in the form shown, since modifications therein may be made without 40 departing from the spirit of the invention.

I claim:

In hand brake mechanism, the combination of a frame having an integrally formed rear wall and end walls with an upper bridge plate rigidly 45 connected to the end walls and extending across the front of the frame between the end walls, a hand wheel shaft having its rear end journaled within the rear wall and its intermediate portion journaled within the upper bridge plate and ex- 50 tending forwardly therefrom, a toothed pinion rigidly secured to the hand wheel shaft, a ratchet wheel rigidly secured to the hand wheel shaft, a dog journaled within the upper portion of the frame between the rear wall and the upper bridge 55 plate and an externally located handle for actuating the dog, a hand wheel rigidly secured to the forward portion of the hand wheel shaft external- 60 ly of the frame, winding mechanism in train with the pinion, and a cover plate removably secured to the front of the frame and overlying the upper bridge plate.

RAYMOND C. O'CONNOR.
